(57) **CLAIM**

I claim the ornamental design for a pencil grip, as shown and described.

DESCRIPTION

FIG. 1 is a perspective view of the pencil grip showing my new design;

FIG. 2 is another perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is another perspective view thereof.

The broken lines showing a pencil in FIG. 1 and a pencil in a hand in FIG. 9 are included for the purpose of showing environmental features that form no part of the claimed design.

1 Claim, 6 Drawing Sheets**FIG. 1**

FIG. 2

FIG. 3

FIG. 4

FIG. 5

FIG. 6

FIG. 7

FIG. 8

FIG. 9
